GEORGE D. HENRY, OF KANSAS CITY, MISSOURI, ASSIGNOR TO SWIFT FLY SWATTER MANUFACTURING COMPANY, OF KANSAS CITY, MISSOURI, A CORPORATION OF MISSOURI.

WIRE-TWISTING MACHINE.

1,186,781.

Specification of Letters Patent. Patented June 13, 1916.

Application filed May 10, 1915. Serial No. 27,175.

To all whom it may concern:

Be it known that I, GEORGE D. HENRY, a citizen of the United States, residing at Kansas City, in the county of Jackson and 5 State of Missouri, have invented certain new and useful Improvements in Wire-Twisting Machines; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to a wire twisting machine, and more particularly to a machine for twisting wire to form a handle, or the like; the principal object of the invention being to provide means for twisting 20 strands of wire evenly so that the twisting is equal, as distinguished from one strand being twisted upon the other.

The present embodiment of the invention is particularly adapted for twisting the wire 25 strands of a handle having a triangular head, and one of the objects of the invention is to provide a holder for the head that will present the wire strands to a mandrel so that the strands may be properly grasped, 30 which will hold the head during the twisting operation and automatically recede under the twisting thrust, and which will automatically eject the formed handle when the twisting has been completed.

35 In accomplishing these and other objects of the invention, I have provided improved details of structure, the preferred forms of which are illustrated in the accompanying drawings, wherein:—

40 Figure I is a perspective view of a wire twisting machine containing my improvements, showing a wire handle in the process of formation. Fig. II is an enlarged detail perspective of the head holder, with an un-twisted handle in place prior to the closing of the holder. Fig. III is a longitudinal sectional view of the operative parts of the machine indicating its manner of use. Fig. 45 IV is an enlarged detail perspective of the holder and mandrel, showing their relation to a partially twisted wire.

50 Referring more in detail to the drawings:—1 designates a skeleton platform, which is supported at a suitable working height from a floor by legs 2, and supported

at one end of the platform is a longitudinal guide 3 comprising spaced angle irons 4 upon and within which a holder plate 5 is adapted for support and travel.

Fixed on the plate 5, adjacent the inner 60 edge thereof, is a base 7 that supports a triangular head block 8, with the apex of the block pointed inwardly and arranged adjacent the inner edge of the plate 7; a rail 9 being fixed to the plate 7 adjacent one edge 65 of the block to form a channel 10 therebetween for receiving one of the wire strands of the handle, or like body, which is to be formed in the machine, and the edge of the block opposite the rail having an incut re- 70 cess 11 for receiving a keeper lip on a co-operating handle member, presently described; and the said block being also provided with an upstanding post 12, which is preferably arranged adjacent the apex and 75 is adapted for projection through a guide aperture in the other holder part.

Spaced rearwardly from the plate 7 and fixed to the slide 5 is a block 14, and hinged to the block and adapted for swinging between the forward edge thereof and the rear edge of the plate 7, is a head 15, which is adapted to seat on the slide between the block 14 and plate 7, and is of a thickness 80 equal to the combined thickness of the plate 85 7 and head 8, so that when the head 15 is down its upper surface will be in a plane with the top of the block 14 and head 8.

The block 14 has a socket 16 in its forward edge within which is located a coil 90 spring 17 that is adapted for engaging the rear edge of the head 15, when the latter is in operative position, in order to exert a tension on the head that will serve to lift the head when the latter is unrestrained, and 95 extending transversely through the forward edge of the head is a groove 18 which is so arranged that when an unformed handle is seated in the holder, with its head portion in the groove 18, the leg strands will 100 lie flat on the top of the plate 7 and at opposite sides of the block 8, as presently described.

The block 15 carries a keeper comprising a strip 19 that is fixed to the block and extends forwardly therefrom at such an angle that its depending side edge flange 20 will lie along and parallel with the socketed edge of the block 8; the body of the strip being of sufficient width to overlie a part of 110

the block 8, and having a recess 21 in its inner edge through which the wire may be observed when the handle is placed in the holder, to determine whether or not the wire is properly seated in its keeper.

Extending inwardly from the lower edge of the side flange 20 is a lip 22 that confines the wire in the keeper strip, and extending downwardly from the end of the strip adjacent the side flange 20 is a tooth 23, which is adapted for properly guiding the wire or handle head and serves as a sharp edge against which the adjacent wire stand abuts when the twisting operation starts, to insure the close initial twist. The body of the strip has an aperture 24 in its forward end for receiving the guide post 12 on the block 8 to insure proper placing of the wire or head of the handle along the triangular block, and for bracing the strip while the wire is being twisted.

The mandrel which co-operates with the holder just described, for effecting the twisting operation, comprises a shaft 26, which is revolvably mounted in bearings 27 on a plate 28 which is rigidly attached to the platform 1 and driven from gearing indicated by the pulley 29 and belt 30; an ordinary clutch 31, operable by a shipper lever 32, being provided for starting and stopping the mandrel. The end of the shaft 26 is preferably conical and has a transverse slot 33 therein terminating at the inner end in a socket 34.

The jaw for effecting the twisting of the wire comprises a head 35 having a flat shank 36 located within the slot 33 in the mandrel shaft and projected into the socket 34; the jaw being attached to the shaft by a pivot pin 38 that preferably extends through the cone lips 39 and through the body shank. The jaw is held in adjusted position by set-screws 40 which extend through the shaft 26 from opposite sides thereof and bear against opposite edges of the jaw shank 36, so that manipulation of the set-screws will turn the jaw on its pivotal mounting to center the axial alinement thereof with the point of the head block on the sliding holder. I also preferably provide the shaft with a set-screw 41 which extends at a right angle to the screws 40 and is adapted for bearing against the flat face of the jaw shank to bind the shank firmly against the face of the slot 33 and hold the jaw rigidly in position.

The jaw proper comprises lips 42 which project oppositely at the inner end of the shank and are curved to form the combined stop and slideways 43; the angle at which the lips extend corresponding to the angle of the head block 8, so that when a handle, or the like, is located in the head block, with the leg strands projected therefrom and the slide moved toward the mandrel, the jaw lips will engage the strands and when the engagement takes place will contact the

strands throughout the length of the lips 42, thereby forming a substantial bearing surface on the jaws that will tend to steady the strands during the twisting operation.

In using the device, presuming the parts to be constructed and assembled as described, a body, such as the unformed handle, is placed in the hinged block and held by the keeper strip, so that when the block is moved down to the head block 8, one of the strands will lie along the socketed edge of the head block and the other in the channel between the head block and the rail 9; the post on the head block projecting through the socket in the keeper strip to properly position the strip and handle head. With the parts so arranged, the leg strands diverge from the end of the slide and form a point concentric with the mandrel jaw, so that when the slide is moved along its guide, the center of the head will be moved toward the center of the jaws, with the result that, when the slide is brought into close relation to the mandrel, the jaw lips will engage the wire strands and grip the same so that rotation of the mandrel will turn the wire strands and cause them to twist about each other; the concentric arrangement of the holder and mandrel insuring an equal twist on both strands. As the twisting continues, the slide is forced backwardly along its guide so that the continued rotation of the mandrel feeds the wire strands through the jaw lips until one of the strands has passed out of contact with its lip.

When spring wire is used, release of one of the strands from its jaw lip allows the strand to spring outwardly and thereby throw the other strand from the opposite lip, this resiliency also tending to lift the holder plate; the lifting of the plate being supplemented by the spring 17 so that the plate is thrown up off of the head block 8, and the twisted handle automatically ejected from the holder. This automatic ejection facilitates the operation of the machine as it eliminates the necessity of removing the twisted handle; the operator being able to use his hands for feeding, without the necessity of cleaning the machine in order to make a place for a subsequent wire.

By mounting the mandrel body adjustably in its shaft, the jaw may be centered relative to the triangular holder so that when the jaw takes hold of the wire strands it will exert equal pressure on the strands at opposite sides of the axial line, so that the strands are bent evenly and equally, as distinguished from one being bent about the other, thereby providing a stiffer, more substantial and more sightly handle.

Should the jaw become loose or out of center it can be easily returned to the proper position by manipulation of the set-screws.

Having thus described my invention, what

I claim as new therein and desire to secure by Letters-Patent, is:

1. The combination with a jaw, of a work holder arranged to hold wire strands in centered relation to the jaw, one of said members being rotatable and the other freely movable longitudinally, whereby the jaw may grasp the strands simultaneously and twisting of the wire may effect feeding 10 travel of the longitudinal member.

2. The combination with a jaw, of a work holder arranged to hold wire strands crossed in centered relation to the jaw, one of said members being rotatable and the other freely 15 movable longitudinally, whereby the jaw may grasp the strands simultaneously and twisting of the wire may effect feeding travel of the longitudinal member.

3. The combination with a rotatable jaw, 20 of a guide, and a work holder arranged for holding wire strands in centered relation to the jaw and freely movable in the guide, whereby the jaw may grasp the strands simultaneously and whereby the holder is 25 movable in the guide by twisting thrust from the strands.

4. The combination with a wire holder comprising a head block, of a rotatable jaw arranged concentrically with the head block, 30 and having opposed lips comprising gripping and slide surfaces arranged at such angle to each other that the extended planes of the gripping and slide surfaces meet in advance of the jaw and in the extended axis 35 thereof.

5. The combination with a holder, of a rotatable shaft having a transverse slot in its free end, a jaw having a shank pivotally mounted in said slot, and adjusting members 40 carried by the shaft and engaging opposite edges of the jaw shank.

6. The combination with a holder, of a rotatable shaft having a slot in its free end, a jaw having a shank located in said slot, 45 and set-screws carried by the shaft and extended into the slot for engaging the shank, for the purpose set forth.

7. The combination with a holder, of a rotatable shaft having a slot in its free end, 50 a jaw having a shank located in said slot, and a set-screw carried by the shaft and engaging a flat face of the shank to bind the latter to the shaft.

8. The combination with a head block, of 55 a rail spaced from one edge of the block, a wire holder movable toward and from the head, and a rotatable jaw in co-operative relation to the head block.

9. The combination with a head block, of 60 means at one edge of the block for holding a wire to the block, a keeper movable toward and from the head block and comprising

means for retaining a wire at the side of the head block opposite said rail, and a rotatable jaw in co-operative relation to the 65 head block.

10. The combination with a head block having a rail spaced from one end thereof to form a channel, of a wire holder movable toward and from the head block and comprising a keeper strip having a stop flange 70 for retaining a wire at the edge of the head block opposite said rail.

11. The combination with a head block having a socket at one edge, of a rail spaced 75 from the opposite edge of the head block, a wire holder comprising a strip having a depending edge flange; the latter having an inturned supporting lip adapted for seating in the socket in said head flange when the 80 parts are in co-operative relation, and a rotatable jaw in co-operative relation to the head block.

12. The combination with a head block having an upstanding post, of means for 85 confining a wire along the head block, a wire holder having an aperture for receiving the head block post, and having a stop flange and supporting lip for co-operation with the wire retaining means on the head block, and 90 a rotatable jaw in co-operative relation to the head block.

13. The combination with a head block, of a holder comprising a head movable toward and from the head block, and having 95 an edge groove for holding a wire, a strip on the grooved head having a stop flange and supporting lip, and a rotatable jaw in co-operative relation to the holder.

14. The combination with a head block, 100 of a hinged head movable into and from the plane of the head block, means for yieldingly urging the head out of alignment with the head block, means on the head for confining a wire to the head block, and a jaw 105 in co-operative relation to the head block.

15. The combination with a slide, of a head block fixed on the slide and having a rail spaced from one edge to form a channel, a head hingedly mounted on the slide and 110 movable into and from horizontal relation to the head block; the forward edge of the hinged member having a transverse groove for seating a wire to position one strand of the wire within the head block channel, 115 means on the hinged member for supporting and confining the opposite strand of said wire, and a rotatable jaw arranged concentrically to the block, and having opposed lips for engaging opposite strands of said 120 wire when the block is moved toward the jaw.

In testimony whereof I affix my signature.
GEORGE D. HENRY.
